UNITED STATES PATENT OFFICE.

WILLIAM JAMES TOLLERTON, OF CHICAGO, ILLINOIS.

LOCOMOTIVE SMOKE-BOX.

1,234,235.

Specification of Letters Patent. Patented July 24, 1917.

Application filed August 7, 1915. Serial No. 44,148.

To all whom it may concern:

Be it known that I, WILLIAM JAMES TOLLERTON, a citizen of the United States, residing at Chicago, in the county of Cook and State of Illinois, have invented new and useful Improvements in Locomotive Smoke-Boxes, of which the following is a full, clear, and exact description.

My invention relates to the smoke-boxes of railroad locomotives and engines, and particularly to the construction of the spark-arrester therein and the relative position of the same to the door in the front end of the smoke-box.

The smoke-box of a modern locomotive is a very crowded compartment and under the most favorable conditions it is difficult to do repairing therein. Heretofore, when the spark-arrester needed repairs, it was customary for the mechanic to crawl into the smoke-box, or even into the spark-arrester itself, and, owing to the limited space, to awkwardly attend to such repairing as was necessary, oftentimes in such stifling heat and soot as to seriously endanger his health. When it was desired to repair the superheater, which is located to the rear of the spark-arrester, it was necessary to dismantle the spark-arrester and remove it piece by piece, or to remove the entire front end of the locomotive and then remove the spark-arrester. The front ends of locomotives usually weigh over a thousand pounds (1000 lbs.) avoirdupois, more or less, and as very few round-houses are provided with overhead crane service the removal and replacing of said front end is a great strain on the workmen and very dangerous.

The object of my invention is to overcome these difficulties and to so construct the spark-arrester and provide a suitably closed lining opening in the front end of the locomotive that the spark-arrester in its entirety can be removed in a comparatively easy manner out through said opening and repaired, or can be removed in a similar manner to afford easy access to the superheater, and then replaced in its entirety without the exercise of great physical strain. In addition to these benefits, the employment of the special form of spark-arrester which my invention makes desirable resists the discharge of the sparks and cinders while permitting the free exhaust of the gaseous products of combustion. These and other objects I accomplish by the means

hereinafter fully described, and as particularly pointed out in the claims.

In the drawings:

Figure 1 is a longitudinal section through the front end of a locomotive boiler and smoke-box embodying my invention.

Fig. 2 is a transverse section thereof taken on dotted line 2—2, Fig. 1.

Fig. 3 is a horizontal section through the door in the front end of the spark-arrester, drawn to a larger scale.

Fig. 4 is a plan view of the nozzle of the exhaust stand removed from the smoke-box.

Fig. 5 is a vertical section of a broken away portion of the nozzle and saddle drawn to a larger scale.

Figs. 6, 7 and 8 are outline drawings of the front end of the spark-arrester showing different shapes thereof.

Figs. 9, 10 and 11 are side views of the spark-arrester shown in Figs. 6, 7 and 8, respectively.

Fig. 12 is a diagrammatical view of the front end of a locomotive in outline showing the manner of operating my improvements.

Referring to the drawings, A represents the shell of the forward end of a locomotive; B represents the front tube-sheet of the boiler; C represents the front end-plate; D represents the door closing the opening in said front end-plate C through which access is had to the smoke-box enclosed between the latter and sheet B, and E represents the superheater located in the rear upper portion of the smoke-box. The superheater, shown in the drawings, is connected to the dry-pipe *a* of the boiler and is provided with return superheater tubes *b* that traverse the enlarged flues *c*, but as it is obvious that any superheater can be used in any locomotive to which my improvements are applied, I do not desire to be confined to the particular type of superheater above referred to. The superheater is separated from the remainder of the smoke-box by a vertically disposed diaphragm 3 the edges of the upper and side portions of which are suitably secured to the inner circumference of shell A, and which extends down to a suitable point above the bottom of the smoke-box, say, to about the horizontal plane of the bottom of the spark-arrester, (which will hereinafter be described), where it is connected to a transverse angle-iron bar 4, which bridges across the smoke-

box and has its ends suitably connected to the sides of the shell. The bottom of this superheater chamber consists of a downwardly inclined transversely disposed plate 5, the rear edge of which comes in contact with the front sheet of the boiler just below the plane of the enlarged tubes that are traversed by the superheater tubes, and has its lower front edge terminate in substantially the same horizontal plane as angle-bar 4. There is a space left between the front edge of inclined plate 5 and said bar 4 through which the products of combustion from the boiler flues discharge, and this discharge opening is controlled by a butterfly damper 6 the transverse shaft of which is journaled in suitable bearings in the shell of the smoke-box and has one end (not shown) extend through its bearings to enable it to be manipulated from the outside. When closed the forward wing of this damper engages the underside of angle-bar 4.

The horizontal flange of angle-bar 4 rests upon the rear edge of a horizontally disposed sheet metal table 7, which latter extends from side to side of the smoke-box and has its end edges secured to and supported by angle-iron brackets 8. It has a central opening 9 therein to accommodate the top of the nozzle 10 of the exhaust-stand 11, and a suitable distance in front of said exhaust-stand and nozzle it rests upon and is supported by a transverse angle-bar 12, which latter in section is of an obtuse angular shape, and has its angular flange inclined downward, substantially as shown. The forward portion of table 7 extends beyond angle-bar 12 and is inclined downward to form an apron 13, and this apron is provided with a series of vertically elongated openings 14 for the reception of suitable bolts 15, by means of which an apron extension 16 consisting of a transverse flat plate can be adjusted vertically to regulate the space between its lower horizontal edge and the lower segment of the shell of the smoke-box out through which the products of combustion from the flues of the boiler pass in transit to the smoke stack 17.

Stack 17 is similar in construction to a type now in extensive use, and its lower portion, below the flanges thereof that rest upon the shell of the smoke-box, enters the smoke box and has a frustum shaped stack extension 18 secured thereto. The lower end of this extension is provided with a similar flange that is seated upon and secured to the margins of a suitable opening in the top of a tubular spark-arrester G in alignment with the vertical axis of the exhaust-stand 11 and its nozzle 10. The axis of this spark-arrester, is preferably, horizontal, and is usually in a horizontal plane above the axis of the shell of the smoke-box and in alignment

with the axis of door D closing the opening in the front end-plate C of the locomotive, which latter is of a sufficient diameter to permit of the spark-arrester being withdrawn.

The shell of this spark-arrester consists of wire-netting or other suitable foraminous material, and it may be perfectly cylindrical, or elliptical, or rectangular, or polygonal in cross-section, or of any other desired shape in cross-section, preferably with its axis horizontal to facilitate its being removed longitudinally out through door D. I prefer, however, to taper this spark-arrester from its front end to its rear end and to so arrange it that its lowest segment will be horizontal and its uppermost segment inclined downward from the front to the rear end thereof.

The flanged lower end of stack-extension 18 is secured to the netting of the spark-arrester by bolts 19, which latter extend down through its lower flange and said netting, and through a flat annular ring 20, and have suitable nuts 21 on their lower ends. There is also a suitable opening in the lower segment of the spark-arrester in alignment with the axis of the stack and exhaust-stand 11, and said spark-arrester rests upon and is supported a suitable distance above table 7 by a suitable rectangular shaped saddle 22, the bottom of which latter is provided with a comparatively large opening 23 up through which nozzle 10 discharges, and the frame of which surrounding this opening is Z-shaped in cross-section. The upper edges 24 of nozzle 10 are flanged horizontally outward and the bottom or inwardly projecting flange of the Z-shaped frame of saddle 22 is bolted to said flanged edges 24. If desired the nozzle and saddle could be combined in one casting and the necessity of bolting them together be avoided. A suitably shaped plate 25 is clamped between the saddle and the nozzle, the dimensions of which are sufficient to close opening 9 in table 7 up through which nozzle 10 discharges, substantially as shown. The upper outwardly projecting flanges 26 of the saddle are secured to the netting of the spark-arrester by means of bolts 27 that extend therethrough and through said netting and through the rectangular liner 28, substantially as shown. Just below flange 24, nozzle 10 is provided with an annular chamber 29 which is supplied with saturated steam from the boiler or dry steam from the superheater by a pipe 30 and is provided with a series of discharge jets 31 surrounding its discharge opening that assist in the discharge of the exhaust through the stack.

The front segment of the portion of stack 17 depending into the smoke-box is provided with a boss 32 that supports the rear

end of a longitudinally disposed bar 33, which latter is, preferably, made of angle-iron and has its forward end inserted in and suitably secured in a boss 34 secured either 5 to the front ring 35 of the shell of the smoke-box or to the front end-plate C. In front of the stack-extension 18, an eye 36 is secured to the uppermost segment of the spark-arrester, which has a threaded shank 10 extending through the netting and provided with a nut on the underside of the same. The eye on the lower end of a hook 37 is linked to this eye 36 and the upper bent end of this hook engages a ring 38 that surrounds 15 and is adapted to slide back and forth on bar 33.

I have shown the rear end 39 of the spark-arrester of imperforate sheet metal, but it is obvious that it may be made of netting, if 20 desired.

The front end of the spark-arrester is, preferably, made of wire netting, and has a doorway or opening therein, which is, preferably, rectangular and is surrounded 25 by a rectangular metal frame. The lower horizontal member 42 and the vertical members 43 of this frame are Z-shape in section; one of the flanges of these members being riveted to the netting and the other parallel 30 offset flange 44 thereof projecting inward over and in front of the edges of the doorway. The door 45 for closing this doorway opening is also made of wire netting and its edges are bound by a rectangular metal 35 frame the lower horizontal portion 46 of which and the vertical portions 47, 47, of which are Y-shaped in cross-section, with the bifurcated or divided members extending outward in planes parallel to the netting 40 to which latter the single member is riveted or otherwise suitably secured. The upper horizontal member of the doorway frame is flat and is a continuation only of the inner flange of the Z-sectioned side members 45 thereof, and the upper member of the door is also flat and constitutes a continuation of the single member of the Y-shaped side sections thereof. The divided member 50 of the sides of the frame of the door engages and slides up and down on the outer flanges of the sides of the frame of the doorway when the same is opened or closed, and when said door is down the divisions of the divided member of the Y-section lower edge 55 of the door straddle and are supported by the outer flange of the Z-sectioned lower member of the doorway frame. In order to raise this door 45 up or down, it is provided with a handle 48. When raised a nail 60 driven through the netting of the door and of the end of the spark-arrester will hold it up. When the nail or other support is removed gravity will close said door. While I prefer to construct this door as just de-

scribed, it is obvious it may be constructed 65 in any other suitable manner.

To utilize my invention either for the purpose of repairing the spark-arrester or for repairing the superheater or other features of the interior of the smoke-box, the 70 door in the front-plate is opened, and then the workman opens the spark arrester door and reaches into the same and removes the bolts that secure it to saddle 22 and to the stack-extension. The handle is then 75 seized and the spark-arrester in its entirety is then pulled forward out through the opening in front-plate C until the forward movement of the suspending hook 37 is stopped by coming in contact with the forward supporting boss 34 of the tram-bar, or until, in the judgment of the workmen, the spark-arrester is in the proper position to enable them to reach in through the opening in the front-plate and release hook 37 from bar 80 33. Making the spark-arrester tubular enables it to be made very compact, and greatly reduces the number of seams, which, in spark-arresters now in common use, is the invariable cause of front ends throwing 85 sparks, and this tubular shape facilitates its removal through opening in the front-plate. Making the spark-arrester practically entirely of wire netting or other foraminous material presents, particularly in the preferred frustum of a cone-shape, or in the cylindrical forms, a foraminous surface 90 which retards and arrests the expelled solid products of combustion in a much more satisfactory manner than the flat foraminous 95 surface of spark arresters now in general use.

When the repairs have been made either to the superheater or other features contained in the smoke-box, or to the spark-arrester itself, the rear end of the latter is inserted in the opening of the front-plate and it is shoved back until it is in position for the suspending hook thereof to be replaced on the tram-bar, and then, when this 105 is done, the spark-arrester is pushed back until it is in its proper assembled position relative to the saddle and the stack-extension, and then it is bolted, in the manner hereinbefore explained, to those members, 110 115 and door D closed and fastened.

It will be understood that the transverse section of the spark-arrester will be such as to best fit the design of the features of its environs and that by making its sides of one 120 piece a great elimination of joints and seams is accomplished, and attention is called to the fact that the manner in which it is supported allows a greater area of foraminous spark-arrester surface and permits it to fit 125 over and to be used in connection with the exhaust nozzles now in extensive use with little or no change, and that the removal of

this spark-arrester in its entirety is accomplished by the removal of but a very few bolts.

What I claim as new is:—

- 5 1. A locomotive boiler comprising a smoke-box, a plate for closing the front end thereof having a door-opening therein, a door for closing said opening, a smoke-stack having a downward extension entering said smoke-box, an exhaust steam nozzle in the lower part of said smoke-box, and a longitudinally disposed tubular spark-arrester longitudinally removable between said nozzle and stack extension, the transverse dimensions of which are less than the area of said door opening through which latter it is removable endwise in its entirety.
- 10 2. A locomotive boiler comprising a smoke-box, a front-plate closing the front end of the same and having a door opening therein, a door for closing said opening, a smoke-stack having an extension entering said smoke-box, a nozzle in the lower part of said smoke-stack opposite said stack, a longitudinally disposed frustum-shaped spark-arrester the transverse dimensions of which are less than the area of said opening, and means for detachably securing said spark-arrester to said stack-extension and nozzle, which spark-arrester is adapted when detached therefrom to be moved endwise in its entirety through said door-opening independently of said door.
- 15 3. A locomotive boiler comprising a smoke-box having a closed front end that has an opening therein, a door for closing said opening, a smoke-stack projecting from the top of the smoke-box, an exhaust-nozzle in the bottom of said smoke-box in vertical alignment with said stack, a saddle removably attached to the top of said nozzle, a longitudinally disposed tubular spark-arrester supported by and between said stack and saddle to the horizontal axis of which its axis is substantially at right angles and in alignment with said opening through which it is adapted to be moved endwise in its entirety independently of said door, a longitudinally disposed bar connecting said stack and front of the smoke-box, and means slidably mounted on said bar for suspending said spark-arrester.
- 20 4. In a locomotive boiler, a smoke-box, a front end-plate for the same having an opening therein, a door for closing said opening, a smoke-stack, an extension therefor depending into said smoke-box the lower edges of which are flanged outward, and an exhaust nozzle in the lower part of said box, in combination with a tubular spark-arrester which is substantially cylindrical and less in diameter than the transverse dimen-

sions of said opening and which has its axis horizontal and its sides foraminous from its front to its rear closed end; said spark-arrester being removably secured to the flanged edges of said superposed stack-extension and indirectly supported by and removably secured to the upper end of said nozzle and adapted to be removed by endwise movement in its entirety out through said opening.

5. In a locomotive boiler, a smoke-box, a front end-plate for the same having an opening therein, a smoke-stack, an extension therefor depending into said smoke-box and having its lower edges flanged, and an exhaust nozzle in the lower part of said box, in combination with a tubular spark-arrester the transverse contours of which are substantially circular throughout its length and less in diameter than the transverse dimensions of said opening but has its upper side inclined downward from its front to its rear closed end, and has its axis horizontal and its sides foraminous throughout its length; said spark-arrester being directly removably secured to the lower flanged edges of said superposed stack-extension and supported by and indirectly and removably secured to the upper end of said nozzle and adapted to be removed by an endwise movement in its entirety out through said opening.

6. In a locomotive boiler, a smoke-box, a front end-plate for the same having an opening therein, a smoke-stack, an extension therefor depending into said smoke-box the lower edges of which are flanged, an exhaust nozzle in the lower part of said box, and a saddle having flanged upper edges and mounted upon and removably secured to the upper end of said nozzle, in combination with a tubular spark-arrester the transverse contours of which are substantially circular throughout its length and less in diameter than the transverse dimensions of said opening and has its upper side inclined downward from its front to its rear closed end and has its axis horizontal and its sides foraminous throughout its length; said spark-arrester being directly removably secured to the flanged lower edges of said superposed stack-extension and supported by and removably secured upon said saddle and adapted to be removed endwise in its entirety out through said opening independently of said door.

In witness whereof I have hereunto set my hand this 2nd day of August, 1915.

WILLIAM JAMES TOLLERTON.
